UNITED STATES PATENT OFFICE.

ALBERT CERFVOL, OF BARKING, ENGLAND, ASSIGNOR OF ONE-FIFTH TO JOHN ALEXANDER FISHER, ONE-FIFTH TO FREDERICK WILLIAM SHEARS, ONE-FIFTH TO EDWARD LUMSDEN, AND ONE-FIFTH TO CHARLES RAYMOND, ALL OF LONDON, ENGLAND.

BLADE FOR PROPELLERS, VENTILATING FANS, AND THE LIKE.

Application filed July 23, 1926, Serial No. 124,497, and in Great Britain July 7, 1926.

The object of this invention is to construct a blade for air propellers, ventilating fans and the like, whereby perfect flexibility along the whole of the blade is maintained 5 under all conditions of working, thereby materially increasing the efficiency of working of such a blade.

According to this invention the blade is composed of a foundation of a multiple of 10 tapered springy rods secured at the desired distances apart to a rigid support which is connected to a carrying boss secured to the driving shaft.

These rods are formed slightly fan shaped 15 and are connected together at their free or smaller ends by suitable flexible or other connections and the whole or a greater part of such rods are covered or enclosed with a flexible, springy or jointed material, so connected as to allow of a certain movement of each rod individually or collectively and of returning or allowing of each rod returning to its normal position.

The covering may be secured together at 25 each side of each rod so that each rod is in its own pocket or the whole rod may be covered and the spaces between each rod filled in which springy or resilient means to allow of the movement and return of the 30 rods to their normal position.

It is preferred that the blade and its boss be connected to the driving shaft by spring controlled means to which there is an imaginary or positive hinged line running parallel with the axis of rotation, that is to say if the bosses carrying the blades are connected direct to the driving shaft through springy or flexible means or the boss can be hinged to the means on the shaft, in which 40 case the action of the blades is further controlled by springs and in both cases each blade is given a slight oscillatory movement about its mean position, in addition to which the action of the air during revolution of 45 the blades acts on said blades to cause them to adapt themselves in surface condition to obtain proper action against the air and thus more efficiency in action.

The invention will be more particularly 50 understood from the following description aided by the annexed drawings in which

Figure 1 is a plan of a blade partly covered with flexible fabric, part being bro-

ken to show link connection with the free ends of the rods. 55

Figure 2 is a section on the line *a a* of Figure 1.

Figure 3 is a section on the line *b b* of Figure 1.

Figure 4 is a section on the line *c c* of Figure 1. 60

Figure 5 is an elevation of a portion of a blade, and showing a spring means positioned between each rod.

Figure 6 is a section on the line *d d* of Figure 5. 65

Figure 7 is a plan of the outer or top end of a blade showing a modified means of constructing and connecting the ends of the rods. 70

Figure 8 is a plan view of a complete propeller with spring means or connection to the driving shaft.

According to this invention, four tapered springy rods 1 are employed preferably of 75 springy steel and these are screw threaded at their thicker ends and screwed into holes in a support 2, the rods 1 being positioned slightly fan shaped and in the preferred application to the driving shaft 3 each support is connected to a bell crank lever 4 pivoted to an arm 5 of a boss 6 secured to the shaft 3, the free arm of the bell crank lever 4 being pivotally connected by springs 7 to another arm 5^a of the boss 6 as will be 80 understood from Figure 8. 85

Each bell crank lever 4 is screwed into the support 2 and in the construction shown at Figure 1 the end rod 1 is screwed into the bell crank lever 4 and the two arms clamped 90 in the split end of the support 2 by bolt and nut 8.

At some little distance from the support 2 and embracing the rod is what might be termed a flexible stiffener i. e. two strips of 95 india rubber 9, 9, see Figure 3, embracing the rods and held thereto by rivets 10 passed between the rods 1 or in lieu thereof, helical springs 11 may be positioned between the rods 1 and the whole covered by a strip 12— 100 the helical springs and strip being kept in place by rivets 13 (see Figure 6).

The free and smaller ends of the rods 1 are connected together by links 14, these being loosely attached to allow of a movement of either or all of the rods 1, and from 105

just beyond the stiffener 9 the remainder of the blade including the links are covered on both sides by a flexible fabric 15 which in addition to being cemented together and to the rods 1, are sewn along the sides of the rods 1 as indicated by the dotted lines 16 so that the rods 1 are positioned in pockets, whereby they can always be kept in their proper position with regard to the covering 15.

Instead of the smaller ends of the rods 1 being shaped and connected together as at Figure 1, the two outside rods may be curved inwards and the two central rods 15 made shorter and the whole connected by a flexible wiring 14 as shown in Figure 7 or such connections may be by wire links.

What I do claim as my invention and desire to claim is:—

20 1. A blade for propellers, ventilating fans, and the like, comprising a series of tapered spring rods, a base support secured to the thicker ends of the rods, said rods being arranged in fan shape, means for connecting the thinner ends of the rods loosely together, a covering consisting of flexible material encasing the rods and secured thereto, and a flexible stiffener embracing all 25 of the rods at a point between the ends of the covering and the support.

2. A blade for propellers, ventilating

fans, and the like, comprising a series of outer and intermediate tapered spring rods a base support secured to the thicker ends of the rods, said rods being arranged in 35 fan shape, a covering consisting of flexible material encasing the rods and secured thereto, the thinner ends of the rods being loosely connected together, and a covering for the rods consisting of a flexible fabric 40 on both sides and secured together by cement and to the rods by rows of stitches on each side of the rods forming pockets therefor.

3. A blade for propellers, ventilating fans 45 and the like, comprising two outer and an intermediate tapered spring rod disposed substantially radially relative to each other, means for securing the thicker inner ends of said rods to form a support therefor, 50 flexible means connecting the outer ends of said rods together and limiting the transverse movement of the rods but permitting a flexing of the blade, means for connecting said support to a driving shaft, a covering consisting of flexible material and encasing the rods secured thereto, and a flexible 55 stiffener engaging the rods adjacent the support.

In testimony whereof I have hereunto set 60 my hand.

ALBERT CERFVOL.
